UNITED STATES PATENT OFFICE.

PETER KRUSE, OF BROOKLYN, NEW YORK, ASSIGNOR TO E. W. BLISS COMPANY, OF BROOKLYN, NEW YORK, A CORPORATION OF WEST VIRGINIA.

MACHINE FOR FLANGING CAN-BODIES OR THE LIKE.

1,263,076.

Specification of Letters Patent. Patented Apr. 16, 1918.

Application filed December 18, 1916. Serial No. 137,635.

To all whom it may concern:

Be it known that I, PETER KRUSE, a citizen of the United States of America, residing in the borough of Brooklyn, county of 5 Kings, city and State of New York, have invented certain new and useful Improvements in Machines for Flanging Can-Bodies or the like, of which the following is a specification.

10 The present invention relates to a machine for flanging can-bodies or the like, and aims to provide improvements therein.

The present improvements are especially applicable to the flanging of polygonal can-bodies, and, in particular, of so-called "square" can-bodies. The present invention provides a continuously operating machine capable of continuously flanging polygonal can-bodies. The machine is hence one which 20 acts to rapidly perform the operation of flanging polygonal can-bodies.

The invention further provides an improved die for use in forming flanges on polygonal can-bodies.

25 Other features of improvement will hereinafter appear and be set forth in the claims hereto annexed.

An embodiment of the invention is illustrated in the accompanying drawings.

30 Referring to the accompanying drawings, Figure 1 is a view of a machine embodying the invention, parts being shown in elevation, and parts in vertical section;

Fig. 2 is a cross-sectional view on the line 35 2—2, Fig. 1;

Fig. 3 is a view, partly in section and partly in elevation, showing in detail the dies and holders or braces which perform the flanging operation.

40 Figs. 4, 5 and 6 are detail views showing the improved die.

Upon a rotatable shaft 1 is mounted a plurality of holder parts 2, the holder-parts being mounted preferably through the intermediary of a spider 3. The holder-parts 45 2 correspond to the shape of the can-body to be flanged, and are of a contour to permit can-bodies to drop therein.

The shaft 1 is rotated by suitable means, 50 as, for instance, a pulley 4 and gearing 5.

In conjunction with each holder-part 2 there is a complementary holder-part 6, the holder-parts 2 and 6, when together, being adapted to closely surround the exterior 55 sides of a can-body, and brace or hold the

same against displacement during the action of the flanging dies.

The holder-parts 6 are adapted to move with relation to the holder-parts 2 in such manner as to permit of the reception of can-bodies in the holder-parts 2, and to this end the holder-parts 6 are adapted to move to and from closing position, and preferably also to be displaced axially of the holder. The holder-parts 6 are preferably carried 65 by arms 7, which arms are pivoted to allow the holder-parts 6 to move to and from closing position. Means, as bolts 8, are preferably provided for limiting the opening or pivotal movement of the arms 7, and means, 70 as springs 9, are preferably provided for normally pressing the arms 7 to open position. The opening and closing movements of the arms 7 are controlled by cam rails 10, as will be hereinafter explained. Contact with the cam rail 10 is preferably 75 through the medium of a roller 11 upon the arms 7.

The holder part 6 and arms 7 are preferably mounted upon slides 12 mounted in 80 suitable slideways upon a spider 13, fixed upon the shaft 1, and corresponding to and moving with the spider 3 carrying the holder-parts 2.

Mounted upon the shaft 1 are cam blocks 85 15, the cam blocks 15 being immobilized by suitable means, as, for example, the rods 16 which are carried by the pillow blocks or other fixed part of the machine. Cam grooves 17 in each of the cam blocks 15 act 90 upon suitable rollers 18 to displace the slides 12 carrying the holder-parts 6.

20 designates the dies which act upon the edges of the can-bodies to form the flanges thereon. These dies 20 are preferably carried upon a slide 21, slidable in suitable slideways in the spider 13, and are adapted to be reciprocated into and out of bending contact with the edges of the can-bodies by cam grooves 22 in the cam block 15. The 100 slide 21 may be provided with a suitable roller 23 for running in the cam groove 22.

For each holder-part 2 there are preferably two complementary holder-parts 6, one on each side of the machine, together with 105 the parts which carry and operate the holder-parts 6, as hereinbefore described.

In order to obtain the best action of the dies upon the bodies, and to obtain a well flanged body, it is desirable to give the 110

flanging faces a differential contour. On the rounded corners of the body there is a stretching of the metal, as well as a turning over, or bending. There is hence more resistance to the die at this point than at the straight faces, and also liability to distortion. To equalize the resistance and to improve the bending, the turning faces 24 at the corners are usually given a greater radius of curvature than the other portions 25 of the die. The turning faces 24 are preferably made upon separable portions 26 of the die, and fastened thereto by suitable means. This construction preferably permits of adjusting the surfaces 24 with relation to the faces 25, and in the present instance this is conveniently done by placing thin strips of material between the underside of the part 26 and the adjacent face of 20 the main part 20 of the die. This adjustment permits of obtaining the best relation between the flanges on the round parts of the body and those at the other parts of the can-body. For instance, it permits of bringing the edges of the flanges into the same plane. Where necessary to obtain the desired flange, the faces 24 of the die would be made upon a smaller radius than the portions 25.

30 Operation: The can-bodies to be flanged are preferably supplied to the machine through a chute or hopper 30. When one of the rotary holder-parts is beneath the hopper or chute 30, as shown in Fig. 2, the complementary holder-parts 6 are opened by the springs 9 and displaced by the action of the cam groove 17 upon the slide 12, in such manner that a can-body may drop into the holder-part 2 as it passes the chute or hopper. As the holder-part 2 moves past the position just referred to, which may be designated by the numeral I, the slide 12 is moved inward by the cam groove 17, bringing the holder-parts 6 on each side of the axis of the can-body toward one another. At about the same time the rollers 11 come into contact with the cam rails 10 which act to close the holder-parts 6 against the pressure of the springs 9. When the holder-parts 6 are pressed inward around the can-body, so that the can-body is closely confined and prevented from outward bulging, the dies 20 are brought into action by the cam grooves 22 acting upon the rollers 23. 45 The dies 20 act to form a flange upon the edges of the can-bodies, and the holder-parts 2 and 6 prevent the can-bodies from giving or bulging under the action of the dies (positions II, III).

50 After the flanges have been formed, the dies are retracted by the action of the rollers 23 in the cam groove 22, and the holder-parts 6 are opened by the springs 9 (the cam rails 10 permitting this) and displaced by the action of the rollers 18 in the cam

groove 17. When the holder-parts 6 are opened and displaced, as, for example, in the position IV, Fig. 2, the flanged can-bodies may drop from the holder-parts 2, and are preferably received upon a suitable conveyer 31 which carries them from the machine. 70

The holder-parts 6 may remain opened and displaced (positions V, VI) until, and after, the corresponding holder-parts 2 reach the position for receiving the can-bodies, viz., the position I on Fig. 2, whereupon the sequence of operation heretofore described, are repeated. 75

The inventive ideas may receive other 80 mechanical expressions than those herein specifically illustrated and described.

What I claim is:—

1. A machine of the character described, comprising a revoluble holder-part, a complementary revoluble holder-part, the inner faces of said holder-parts inclosing a space polygonal in cross-section, one of said holder-parts being adapted to move relatively to the other, and a flanging die, said 85 complementary holder-parts being adapted to hold a can-body therein against displacement or bulging during the action of said flanging die. 90

2. A machine of the character described, comprising a revoluble holder-part, a complementary revoluble holder-part, the inner faces of said holder-parts inclosing a space polygonal in cross-section, one of said holder-parts being adapted to move to and 100 from position to permit reception and discharge of a can-body, and a flanging die, said complementary holder-parts being adapted to hold a can-body therein against displacement or bulging during the action 105 of said flanging die.

3. A machine of the character described, comprising a revoluble holder-part, a complementary revoluble holder-part, the inner faces of said holder-parts inclosing a space 110 polygonal in cross-section, and means for moving one of said holder-parts to and from position to permit reception and discharge of a can-body, said means comprising a slide carrying one of said holder-parts, a flanging die, a cam for actuating said slide and a cam for actuating said flanging die, said complementary holder-parts being adapted to hold a can-body therein against displacement or bulging during the action 115 120 of said flanging die.

4. A machine of the character described, comprising a revoluble holder-part, a complementary revoluble holder part, the inner faces of said holder-parts inclosing a space 125 polygonal in cross-section, and means for moving one of said holder-parts to and from position to permit reception and discharge of a can-body, said means comprising a movable arm carrying one of the holder- 130

parts, a slide carrying said movable arm, a cam for actuating said movable arm, and a cam for actuating said slide, a flanging die, and a cam for actuating said flanging die, said complementary holder-parts being adapted to hold a can-body therein against displacement or bulging during the action of said flanging die.

5. A machine of the character described, comprising a revoluble holder-part, a pair of complementary revoluble holder-parts, the inner faces of said holder-parts inclosing a space polygonal in cross-section, and means for moving said complementary holder-parts to and from position to permit reception and discharge of a can-body, said means comprising a pivotally mounted arm carrying each of the complementary holder-parts, slides upon which said arms are 10 mounted, a cam rail adapted to move said arms and holder-parts to closing position, a cam for actuating each of said slides, a reciprocating flanging die in conjunction with each holder, and means for reciprocating

said flanging die, said complementary holder-parts being adapted to hold a can-body therein against displacement or bulging during the action of said flanging die.

6. A machine of the character described, comprising a revoluble holder-part, a complementary revoluble holder-part, the inner faces of said holder-part inclosing a space polygonal in cross-section, one of said holder-parts being adapted to move relatively to the other, and a flanging die, said die having differential bending faces, said complementary holder-parts being adapted to hold a can-body therein against displacement or bulging during the action of said flanging die.

15 In witness whereof, I have hereunto signed my name in the presence of two subscribing witnesses.

PETER KRUSE.
